US00D687078S

(12) **United States Design Patent**
Shibata et al.

(10) **Patent No.:** US D687,078 S
(45) **Date of Patent:** ** Jul. 30, 2013

(54) **CUTTING INSERT**

(75) Inventors: **Masahiro Shibata**, Higashiomni (JP);
Kazuki Yamamichi, Higashiomni (JP)

(73) Assignee: **Kyocera Corporation**, Kyoto (JP)

(**) Term: **14 Years**

(21) Appl. No.: **29/409,503**

(22) Filed: **Dec. 23, 2011**

(51) **LOC (9) Cl.** **15-09**

(52) **U.S. Cl.**
USPC **D15/139**

(58) **Field of Classification Search**
USPC D8/70, 71; D15/138, 139, 140; 407/42,
407/112-119

See application file for complete search history.

(57) **CLAIM**

The ornamental design for a cutting insert, as shown and described.

DESCRIPTION

FIG. 1 is a perspective view of a cutting insert;

FIG. 2 is a front view thereof;

FIG. 3 is a left side view thereof, the opposite side being a mirror image of the side shown herein;

FIG. 4 is a top view thereof; and,

FIG. 5 is a bottom view thereof.

The portion shown by broken lines is for illustrative purposes only and forms no part of the claimed design.
